UNITED STATES PATENT OFFICE.

FRANZ TRINKS, OF BRUNSWICK, GERMANY.

CALCULATING-MACHINE.

1,215,219.

Specification of Letters Patent.

Patented Feb. 6, 1917.

Application filed October 23, 1914. Serial No. 868,308.

To all whom it may concern:

Be it known that I, FRANZ TRINKS, manufacturer, citizen of the Duchy of Brunswick, Empire of Germany, residing at 5 Brunswick, Germany, have invented certain new and useful Improvements in Calculating-Machines, of which the following is a specification.

This invention relates to calculating machines, and in particular to the means or mechanism therein comprised for setting up the numbers to be computed on the wheels of the register or totalizer, the invention constituting, in effect, an improvement on, 15 or development of, the construction shown and described in my prior United States Patent, No. 823,375, granted June 12, 1906.

In calculating machines of the type disclosed in said patent, the setting operation 20 is carried out by means of a series of rotatable disks, one for each numeral wheel, these disks, when turned, acting to project outwardly one or more pins associated therewith, according to the particular digits 25 being computed; and at the completion of this preliminary indexing operation, as it may be termed, the main shaft or other actuating element is brought into play, thereby rotating the numeral wheels, 30 through the agency of intermediate gearing, to the extents determined by the set pins. The disks are subsequently returned to their original positions by a resetting device, which acts upon all of them at the 35 same time.

According to the present invention, means are provided whereby a digit to be computed can be directly run up on any selected numeral wheel or wheels, independently of all of the other wheels, and without entailing operation either of the aforementioned setting disks, or of the main actuating element, so that a complete computation can be set up in the register before the 45 main setting and driving mechanisms have been operated, thereby materially simplifying the operation of the machine. Also, the set numeral wheel or wheels may be directly returned to zero individually, without affecting the remaining wheels, or any of them; or, if desired, all of the numeral wheels, may be directly zero-set simultaneously, thereby clearing the register.

An embodiment of the invention is illustrated in the accompanying drawing, in

which Figures 1 and 2 are, respectively, a vertical section and a plan view of the registering mechanism of a calculating machine of the general type disclosed in the patent above identified.

Referring more particularly to said drawing, the register or totalizer of the present construction is shown as comprising a series of digit-bearing numeral or dial wheels 2, loosely mounted on a shaft 1, and having fixed to opposite sides thereof a pair of gears 4 and 7. The gears 4 are those usually employed in the present type of calculating machine, and they are adapted to be engaged, in the case of such machine, by the outwardly-projected pins on the corresponding disks of the main setting or indexing mechanism (not shown), the rotation of said pin-carrying disks, produced consequent upon the operation of the main shaft or other driving element, effecting the rotation of the gears 4 and their attached numeral wheels to extents determined by the numbers of pins set on the disks, as will be understood. Hence, it appears that these gears 4 are directly acted on by the main setting mechanism, and, in turn, form the means whereby the numeral wheels are normally controlled and driven. The usual back-check pawls 3 are preferably provided in connection with the aforesaid gears 4, as shown.

The gears 7 expressly form a part of the improved or added setting and resetting mechanism, and are lacking in the earlier or patented construction, their sole function being to effect the rotation of the numeral wheel when actuated by the devices about to be described. In the construction illustrated, which, for all present purposes may be considered as preferred, the actuating devices consist of gear sectors 5, one individual to each numeral wheel, loosely mounted in an inverted position on a horizontal shaft 10, and normally held in a retracted position with relation to the opposite gears 7, by springs 18. The shaft 10 just referred to, is journaled at its ends in slots provided in the end walls of the casing of the machine, and, hence, is capable of a limited lateral movement toward and from the numeral wheel shaft 1. Normally, however, shaft 10 is pressed toward shaft 1 by means of a spring 14 that bears against the adjacent one of a pair of depending links 110

12 and holds it against a stop 19; said links 12 being connected at their upper ends to the shaft 10 and at their lower ends to a rock shaft 15. This shaft 15 is located 5 parallel with, and close to, the base plate 13, and is equipped with an external crank handle 16, by means of which it may be rocked, for the purpose of forcing the sector shaft 10 away from the numeral wheel shaft 10 1, thereby disengaging all of the sectors at once from the gears 7, said handle moving at such time in the direction of the arrow 17. The unmeshing of the sectors from gears 7, leaves said sectors free to be depressed by their springs 18.

Each of the afore-mentioned gears 7 is provided, for purposes subsequently explained, with a cut-away or mutilated portion 6, such mutilated portion comprising 20 the spaces ordinarily occupied by the teeth corresponding to the digits "7" and "8" on the periphery of the numeral wheel. In the normal position of the parts, shown in Fig. 1,—that is to say, when the machine is 25 cleared, and the "0's" on all of the wheels stand opposite the sight opening 11 in the casing,—the sectors 5 are ineffective or inoperative with relation to the gears 7, since only the mutilated portions 6 of said gears 30 are at that time disposed in the path of the sectors, as will be apparent. Hence, it is necessary to first turn the numeral wheels one step before they can be set by the sectors, this added or initial step being imparted to said wheels by the gears 4, which latter, in the present construction, are driven 35 from the main setting mechanism, thereby exposing a row of "9's" through the sight opening. At the completion of such operation, the teeth corresponding to the "6's" 40 on the numeral wheels will be brought into position for engagement with the uppermost teeth on the sectors, the latter being then rotated in the direction of the arrow 8, by 45 means of their finger-pieces 9, to effect the setting of the numeral wheels for any position between "0" and "8".

The individual rotation of the numeral wheels by the sectors may be utilized, as 50 just stated, to run up a computation on any selected wheel or wheels, and it may also be utilized to zero-set such wheel or wheels, it being understood that in the latter case 55 the wheel has previously been set to expose the desired digit. The turning of the numeral wheels by the sectors during the re-setting or clearing operation, continues until the mutilated portions 6 of the gears 7 60 come opposite the teeth on the sectors, at which time the wheels show their "0's" through the sight opening and the gears cease to move. Means are also provided 65 whereby this clearing of the numeral wheels by the sectors may take place simultaneously for all of said wheels, such means preferably

consisting of a horizontal rod or bar 21, that is disposed parallel with shaft 10 and is suitably connected to the same to be swung or shifted bodily thereby. This bar overlies all of the sectors, as shown in Fig. 1, so that 70 the latter will be rocked upward in the direction of arrow 8 when said shaft 10 is operated by means of the crank handle 20 with which it is equipped externally.

In operation, assuming that all of the numeral wheels stand at zero, and that it is necessary, or desirable, either to set up a complete preliminary computation on the register, prior to actuation of the main setting and driving mechanisms, and independently thereof, or else to set up a particular digit or digits on a certain wheel or wheels for any purpose whatever, the aforesaid main setting mechanism is first operated, in the case of a machine of the Trinks type, to 75 set all of the wheels in their "9" position, this initial operation bringing the teeth at the lower extremities of the mutilated portions 6 of the gears 7 into position for engagement by the uppermost teeth on the sectors 5. The preliminary setting operation just described may, and probably will in practice, be effected at the completion of each 80 day's work, so that the machine will be left ready for the operator to set up any desired number therein on beginning the next 85 day's work.

In any case, however, the gears 7 are brought in this way into operative position with relation to the sectors 5, and the latter 90 are then manipulated individually by means of their finger-pieces 9, to set up the desired digits on the appropriate numeral wheels. The handle 16 is then actuated, 95 with the result that the sector shaft 10 is 100 carried to a position where all of the sectors are disengaged from gears 7 and are immediately restored to normal position automatically by the springs 18, said shaft being likewise returned to normal position by 105 spring 14 when the handle is released. Computation then proceeds in the usual manner. 110

At any time during computation, the numeral wheels may be turned to zero, either 115 individually or collectively, according as the sectors are operated *seriatim* by their finger-pieces 9, or concurrently by the action of the handle 20, the latter serving to actuate the bar 21 which, in turn, rocks all of the sectors in unison. In either instance, the gears 7 are rotated by the sectors, until 120 their mutilated portions 6 come opposite the sectors and preclude further rotation of said gears, the numeral wheels having reached 125 their zero positions at such time.

While the invention is intended primarily for use in connection with a machine of the Trinks type, as represented in the patent specified, it will be understood that no restriction to such use is contemplated. Hence, 130

it is immaterial, as regards the actual features of the invention, just how the driving gears 4 are rotated to position the mutilated gears for engagement with the sectors, since 5 they may obviously be turned by devices other than the usual pin-carrying disks of the Trinks construction.

It will also be apparent from the foregoing, that while the sectors function primarily to initially run up digits on selected numeral wheels, and to subsequently clear any or all of said wheels either individually or simultaneously, they may also be used to correct errors in cases where the digits accidentally registered are higher than those intended, as, for example, where "6" was registered instead of "5", etc. In such case, the wheel on which the error is present, may be turned back one or more steps without 10 affecting any of the other wheels, or necessitating operation of the main setting and driving mechanisms.

I claim:

1. In a calculating machine, the combination, with a series of numeral wheels, each provided upon opposite sides with a pair of gears, one gear of each pair being adapted to drive the associated wheel to different predetermined extents to run up different 25 digits thereon; of a series of individually-operable sectors, one for each wheel, each sector engageable with the other gear of the corresponding pair to alternatively run up a digit on the associated wheel or turn said wheel to zero.

2. In a calculating machine, the combination, with a series of numeral wheels, each provided with a gear; of a series of individually-operable toothed elements engageable with said gears, to rotate the accordant wheels, said gears normally out of position for such engagement; and means whereby said wheels may be rotated to bring said gears into position for such engagement.

3. In a calculating machine, the combination, with a series of numeral wheels each having a gear on one side thereof; of a series of individually-operable toothed elements engageable with said gears, to rotate the accordant wheels, said gears normally out of position for such engagement; and a gear fixed to the opposite side of each wheel from the first-named gear, to rotate said wheel and thereby bring said first-named gear into position for such engagement.

4. In a calculating machine, the combination, with a series of numeral wheels, each provided with a gear having a portion thereof cut away; of a series of individually-operable toothed elements engageable with said gears, to rotate the accordant wheels, said gears normally disposed with their cut-away portions opposite said toothed elements, so as to preclude such engagement; and means whereby said wheels may be ro-

tated so as to bring the teeth of said gears opposite said elements, to permit such engagement.

5. In a calculating machine, the combination, with a series of numeral wheels each provided with a gear; of a series of individually-operable toothed elements, one for each gear, engageable with said gears to rotate said wheels; a common supporting shaft whereon said elements are loosely mounted; and means connected to shift said shaft bodily away from said gears, to disengage said elements therefrom.

6. In a calculating machine, the combination, with a series of numeral wheels each provided with a gear; of a series of individually-operable toothed elements, one for each gear, engageable with said gears to rotate said wheels; a common supporting shaft whereon said elements are loosely mounted; means connected to shift said shaft bodily away from said gears, to disengage said elements therefrom; and means for automatically returning the disengaged elements to normal position.

7. In a calculating machine, the combination, with a series of numeral wheels each provided with a gear; of a series of individually-operable toothed elements, one for each gear, engageable with said gears to rotate said wheels; a common supporting shaft whereon said elements are loosely mounted; means connected to shift said shaft bodily away from said gears, to disengage said elements therefrom; means for automatically returning said shaft to normal position; and a spring individual to each of said elements for automatically restoring the same to normal position upon its disengagement.

8. In a calculating machine, the combination, with a series of numeral wheels, each provided with a gear; of a series of individually-operable toothed elements, one for each gear, engageable with said gears to rotate said wheels; and means for bodily shifting all of said elements away from said gears, to effect their disengagement therefrom.

9. In a calculating machine, the combination, with a series of numeral wheels, each provided with a gear; of a series of individually-operable toothed elements, one for each gear, engageable with said gears to rotate said wheels; means for bodily shifting all of said elements away from said gears, to effect their disengagement therefrom; and means for automatically returning the disengaged elements to normal position.

10. In a calculating machine, the combination, with a series of numeral wheels, each provided with a gear; of a series of individually-operable toothed elements, one for each gear, engageable with said gears to rotate said wheels; a common support therefor; a pair of vertical links connected at one end to said support; a rock shaft to

which said links are connected at the other end; and means for rocking said shaft, to shift said support bodily away from said gears, to disengage said elements therefrom.

- 5 11. In a calculating machine, the combination, with a series of numeral wheels; each provided upon opposite sides with a pair of gears, one gear of each pair being adapted to drive the associated wheel to 10 different predetermined extents to run up different digits thereon, and the other gear of the pair having a mutilated portion; of a series of individually-operable toothed elements, one for each wheel, each of said elements engageable with the mutilated gear 15 of the corresponding pair to run up a digit on the associated wheel, said mutilated gears having their mutilated portions normally disposed opposite said elements to preclude such engagement, but rotatable to bring 20 their toothed portions opposite said elements to permit such engagement.

In testimony whereof I have hereunto set my hand in presence of two subscribing witnesses.

FRANZ TRINKS.
